J. M. ODEN.
HOSE MAKING MACHINE.
APPLICATION FILED MAR. 30, 1918.

1,322,464.

Patented Nov. 18, 1919.

UNITED STATES PATENT OFFICE.

JOHN M. ODEN, OF BROOKLYN, NEW YORK.

HOSE-MAKING MACHINE.

1,322,464.

Specification of Letters Patent.

Patented Nov. 18, 1919.

Application filed March 30, 1918. Serial No. 225,654.

To all whom it may concern:

Be it known that I, JOHN M. ODEN, residing at Brooklyn, in the county of Kings and State of New York, have invented certain new and useful Improvements in Hose-Making Machines, of which the following is a specification.

This invention relates to a hose-making machine.

10 The object of the invention is to provide a simple and efficient machine whereby a coating of rubber or the like may be applied to hose or the like in such manner that the coating is of substantially uniform density throughout, and in which the machine parts employed will not be subject to undue heating during operation.

20 A more detailed object is to provide a machine by which a supply of rubber or the like may be fed to the tube from opposite sides, and to provide feeding means of a character, and in such relation to the point of application, as to serve as efficient agitator and mixer means adapted to improve the 25 uniformity of the application.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will be indicated in the appended claims.

35 In the accompanying drawings which are to be taken as a part of this specification, and in which I have shown merely a preferred form of embodiment of the invention:

40 Figure 1 is a horizontal sectional view through a device constructed in accordance with this invention, the section being taken substantially upon the plane of line I of Fig. 2.

45 Fig. 2 is a vertical sectional view taken substantially upon the plane of line II of Fig. 1, and

Fig. 3 is a detail view of the die employed.

50 In describing the exemplary structure which is illustrated in the drawings, the reference character L indicates the body. The reference character G indicates the head, while the reference character H indicates the tube or the like which is being fed

through the machine to receive its rubber coating 1.

55 The body L is formed with a feed opening 2 extending longitudinally central therethrough through which the tube H passes. At each side of the feed opening is provided a screw pocket 3 containing a 60 screw 4. These screw pockets are arranged in divergent relation so that their forward open ends, as 5, stand nearest to the feed opening, while their rear ends are farthest spaced apart.

65 The screws 4 may be driven in any suitable manner but for convenience are shown to be connected by shafts 6 with gears 7 which are in turn arranged to be driven by a drive gear 8 through the medium of an 70 intermediate pinion 9, the gear 8 and pinion 9 being conveniently illustrated as rotatably mounted upon an extension sleeve 10 projecting from the body L as a continuation of the feed opening 2.

75 The rubber or the like for use in the machine may be fed to the screw pockets through suitable hoppers 11.

The head G comprises a main part 12 having means such as the ears 13 by which 80 it may be bolted to the body L, and a die part 14 carried within the main part 12. The die is removably held in place by means of a screw sleeve 15 and may be laterally adjusted by means of a series of set screws 85 16 carried by the part 12 and engaging peripheral portions of the die at different radial points as is customary in machines of this type.

90 The die is of funnel-shape and the opening 17 at its smaller end is of a size such that it determines the exterior diameter of the cover 1 as said cover emerges through said opening, while the opening 18 at its larger end is such that it embraces the open 95 ends 5 of both of the screw pockets. The walls preferably are curved substantially as illustrated, so as to better facilitate the passage of the rubber toward the opening 17.

A hollow guide member 19 is fixed to the 100 body to form a continuation of the feed opening through the die and into close proximity to the opening 17 of the die. This guide member is tapered so that its forward annular edge is quite thin. At its rear end 105 it is preferably threaded into the body, as at

20, so that it may be readily removed for substituting a guide of a different size in accordance with the size of tube H which is to be covered.

5 It will be noted that in the operation of this machine the rubber from the pockets 3 is fed with great force immediately into the die at substantially diametrically opposite sides of the tube H. It flows in both directions about the guide 19 as it moves the short distance through the die to the opening 17. Rubber from one screw pocket passes upwardly about the guide 19 while other rubber from the same pocket passes downwardly about the guide. These two bodies of rubber meet corresponding bodies from the second screw pocket at a point substantially midway and, due partly to the reducing diameter of the die and partly to the churning, or agitating, action of the closely juxtaposed screws, the joint between the meeting bodies becomes more or less kneaded. A homogeneous union and an even density is thus secured as the joining bodies are forced 25 out through the opening 17.

The disposition of the screw pockets at an acute angle relative to the line of feed of the tube H enables the rubber to move toward and through the opening 17 without material change in its general direction of travel. This also increases the efficiency of the device and provides a structure in which no packing is required between any of the moving parts.

35 As many changes could be made in this construction without departing from the scope of the invention as defined in the following claims, it is intended that all matter contained in the above description or shown 40 in the accompanying drawings, shall be interpreted as illustrative only and not in a limiting sense.

Having thus described my invention, what I claim as new and desire to secure by 45 Letters Patent, is:—

1. A device of the class described comprising a body member having an opening therethrough through which a tube or the like to be covered may be passed, the device having a pair of screw pockets arranged one at each side of said opening, screws within said pockets terminating in close proximity to one end of said opening, and means whereby material fed by 55 said screws will be directed toward the longitudinal axis of said opening.

2. A device of the class described comprising a body member having an opening therethrough through which a tube or the like to be covered may be passed, the device having a pair of screw pockets arranged one at each side of said opening, screws within said pockets, and a die having an opening arranged in alinement with 60 the first opening and being shaped to re-

ceive material from both of said screw pockets.

3. A device of the class described comprising a body member having an opening therethrough through which a tube or the like to which a covering is to be applied, may be passed, the body member having a second opening through which covering material may be fed, means whereby material from the second opening may be directed 75 into position for application to the tube, and agitator means for said material adjacent to the point of application.

4. A device of the class described comprising a body member having an opening 80 therethrough through which a tube or the like to which covering is to be applied may be passed, the body member having a second opening arranged in divergent relation to the first opening through which 85 covering material may be fed, said second opening constituting a screw pocket, a screw rotatably mounted within said pocket adapted for forcing covering material therefrom, means whereby covering material 90 from said screw pocket may be directed into position for application to the tube, and said screw constituting an agitator means for said material adjacent to the point of application. 95

5. A device of the class described comprising a body member having an opening therethrough through which a tube or the like to which covering is to be applied may be passed, the body member having a pair of 100 other openings formed therein arranged in divergent relation to the first opening, through which covering material may be fed, said second openings constituting screw pockets, a screw rotatably mounted within 105 each of said pockets adapted for forcing covering material therefrom, means whereby covering material from said screw pockets collectively may be directed into position for application to the tube, and means for driving said screws uniformly. 110

6. A device of the class described comprising a body member having an opening therethrough through which a tube or the like to which covering is to be applied may be passed, the body member having a pair of other openings formed therein arranged in divergent relation at substantially opposite sides of the first opening through which covering material may be fed, said second 115 openings constituting screw pockets, a screw rotatably mounted within each of said pockets adapted for forcing covering material therefrom, means whereby covering material from said two screw pockets are 120 directed toward the respective sides of the passing tube, and said screws terminating in close proximity to the point of application of the covering material to the tube. 125

7. A device of the class described com- 130

prising a body part and a head part, each of said parts having openings therethrough through which a tube or the like to be covered may be passed, the body part having 5 a plurality of screw pockets formed therein, screws one arranged in each of said screw pockets adapted for forcing covering material from said pockets, and the head part having a part shaped to embrace the dis-

charge openings of all of said screw pockets 10 and to direct the covering material from said pockets into covering position.

In testimony whereof I affix my signature in the presence of two witnesses.

JOHN M. ODEN.
